UNITED STATES PATENT OFFICE.

JOHN H. KLINGSTINE, OF BALTIMORE, MARYLAND, ASSIGNOR TO THE TIN DECORATING COMPANY OF BALTIMORE, OF BALTIMORE, MARYLAND, A CORPORATION OF NEW JERSEY.

INSET SIFTER TOP.

Application filed September 16, 1921. Serial No. 501,042.

To all whom it may concern:

Be it known that I, JOHN H. KLINGSTINE, a citizen of the United States, and resident of Baltimore, Maryland, have invented certain new and useful Improvements in Inset Sifter Tops, of which the following is a specification.

My invention relates to containers, and is especially directed to an improved type 10 of sifter top therefor. A general object of my invention is to provide a top of this nature including the usual dispensing perforations and a manually operated slide cover therefor, which is extremely simple 15 both in arrangement and construction, with the purpose of providing a strong, positive acting slide and a top which can be very cheaply and rapidly manufactured by standard types of machinery.

20 My invention is particularly directed to the provision of a sifter top including a cover of the inset type. In containers employing sifter tops, it is highly desirable to provide for ease in filling combined with 25 a cover tight enough to prevent the escape of even the finest powder; and the friction inset type of top is admirably suited for this purpose, both because of the facility with which a large filling opening is provided, and the tight closure which the employment of this kind of top assures. However, the ordinary sifter top construction is not readily applicable to inset covers, 30 constructions heretofore suggested for the purpose being cumbersome and impractical.

Another important object of my invention, therefore, is to provide an inset friction cover for containers, embodying in the 40 cover a dispensing perforation or perforations provided with a sliding closure.

As covers of this type may be of substantial size, and ordinarily are somewhat larger than the usual perforated tops of 45 dispensing containers, an ancillary object is to provide a slide closure which will operate efficiently and can readily be manufactured for use in a dished top of substantial size.

50 Other objects and advantages of my invention will be apparent from the following description, taken in connection with the accompanying drawings, in which:

Fig. 1 is a perspective view of a container embodying my invention, 55

Fig. 2 is a vertical transverse section through such container, and

Fig. 3 is an enlarged fragmentary vertical section through one side of the cover and slide. 60

My invention is illustrated as applied to a container 10 of the full opening type, provided with straight sides terminating at the top in an outwardly extending bead 11. The cover 12 is of the inset friction type 65 having a bottom 13, side walls 14 adapted to fit tightly against the walls of the container 10, and an outwardly turned bead 15 overlying bead 11 of the container body when the cover is in closed position. This 70 type of cover, often called a friction top, is well known; and it is applied to various types of containers in various ways, to all of which my invention may readily be adapted. 75

I provide a dispensing perforation or perforations 16 in the bottom 13 of the cover, preferably extending over half or less of its area. In connection therewith, I provide a closure plate 17 mounted to 80 slide along the bottom 13 of the cover into position to close or expose the apertures 16, the plate and bottom being so contoured that when in closed position the plate will fit snugly against bottom 13, to prevent 85 escape of any substantial amount of the container contents.

A principal feature of my invention includes the means for mounting plate 17 in the cover. For this purpose I provide walls 90 18 extending upwardly from and preferably integral with the cover bottom 13. These walls form guides between which the plate 17 slides; and preferably constitute the lower portion of cover wall 14. Where 95 the cover slides in a longitudinal rather than a rotary manner, as in the preferred form illustrated, I employ two parallel walls 18, which in the simplest form are constituted from the lower part of walls 100 14 of the cover. Plate 17 extends into proximity to the walls 18 so as to be guided thereby.

I also provide means for retaining plate 17 in close engagement with the cover bottom 13 without interfering with the sliding 105

of the plate. For this purpose, I provide inward projections on walls 18 extending above and in position to engage the upper part of plate 17. These projections are conveniently produced by directing an extension of said walls 18 inwardly, immediately above the edges of plate 17 throughout all or a part of the active guiding portion of said walls 18. Where walls 18 are part of the cover walls, this is readily produced by striking inwardly a bead 19 along each of the guiding walls of the cover; but obviously the guide grooves formed by walls 18 and beads 19 may be produced in the cover walls in various other ways within the skill of an ordinary mechanic.

I preferably provide means for facilitating the manual operation of slide plate 17, as by connecting to or forming from said plate an upwardly projecting tongue 20, which may be rolled over as illustrated, to produce a neat and attractive finger piece. Furthermore, this construction considerably stiffens plate 17 transversely, and tends to prevent it from bulging or becoming bent upwardly away from the dispensing openings 16. Moreover, if desired the parts may be so proportioned that plate 17 will be very slightly curved downwardly by the lateral pressure thereon of walls 18, holding said plate in close contact with the cover bottom 13.

It will be apparent that covers constructed according to my invention may be very readily and rapidly manufactured, particularly in the general form shown in the drawings, in which the only additional operations necessary on an ordinary inset friction top are the production of the perforations 16 and striking up the retaining means 19. Plate 17 is equally simple to manufacture, since it may be made from a single sheet by a simple stamping operation. Furthermore, the cover and slide plate may very readily be assembled, either by locating plate 17 on the cover bottom and then striking up the retaining means 19, or by forming said retaining means in the cover during its regular manufacture, and then utilizing the resiliency of ordinary sheet metal to spring plate 17 into place, the latter operation being particularly effective when such plate is so proportioned that it is normally curved downwardly to some extent, as above indicated. It is of course understood that various other methods of assembly, depending upon the precise construction used, may be employed, my intention being simply to indicate the ease of manufacture and assembly of the preferred form shown.

It will be apparent that numerous variations in my invention can readily be made, both in the arrangement of the guide and retaining means and in the construction of the slide plate. In particular, while I have dis-

closed a longitudinally sliding plate, my invention is not necessarily limited thereto, as a rotating plate can be employed in an embodiment of my invention by any skilled mechanic.

My invention therefore is not limited to the precise form shown, or the modifications therein indicated herein, as numerous other changes and variations therein can readily be made by one skilled in the art within the scope of the following claims.

I claim:

1. A dispensing closure for receptacles of the full opening type having straight side walls and designed for granular or pulverized material, comprising a dished sheet metal body having a substantially flat bottom portion co-extensive with the mouth of the receptacle in which the closure is to be inserted, said bottom portion having one or more dispensing openings, upright side walls surrounding said bottom portion and adapted to fit closely within the upper ends of the side walls of said receptacle with said bottom portion located below the upper edges of said receptacle side walls, and a cover piece slidably located on the outer face of said bottom portion with two opposite edges close to two opposite side walls of the closure, the length of the cover in a direction parallel to said edges being substantially less than the length of said closure bottom in the same direction, said closure side walls having impressed beads near the closure bottom and engaging over said parallel edges of the cover member to retain the latter slidably in position.

2. A dispensing closure for containing receptacles of the full opening type having straight side walls and designed for finely divided material, comprising a dished sheet metal body having a substantially flat bottom portion co-extensive with the mouth of the receptacle in which the closure is adapted to be inserted with a push fit, said bottom portion having a pattern of dispensing openings near one side thereof, upright side walls surrounding said bottom portion and adapted to fit closely within the upper ends of the side walls of said receptacle with said bottom portion located below the upper edges of said receptacle side walls, a cover piece slidably located on the outer face of said bottom portion with two opposite edges close to two opposite side walls of the closure, the length of the cover in a direction parallel to said edges being substantially less than the length of said closure bottom in the same direction, said closure side walls having impressed beads near the closure bottom and arranged to engage over said parallel edges of the cover member to retain the latter slidably in position, and a handle on the cover.

3. A container comprising a body of the

full opening type having straight side walls and an inset top or closure fitting frictionally between the side walls and consisting of a bottom and side walls, and perforate at one end of the bottom, and a sliding cover, opposite side walls of the closure at the top offset inwardly to provide guides for the cover to hold it close to the bottom of the top, said offsets being below the tops of the side walls.

4. In combination with a container comprising a body having an open top and straight side walls and a friction fit closure

for closing the top and comprising a bottom fitting within the top of the body and side walls contacting with the side walls of the body, said body perforate near one end, and a slide for closing the perforate portion, opposite side walls of the closure inwardly offset above the slide and below the tops of the side walls of the closure to form guides for the slide.

Signed at Baltimore, in the city of Baltimore and State of Maryland this 13th day of September, A. D. 1921.

JOHN H. KLINGSTINE.
